SUBBO NIKOLOFF, OF PUTNAM, CONNECTICUT, ASSIGNOR TO LELAND-GIFFORD COMPANY, OF WORCESTER, MASSACHUSETTS, A FIRM CONSISTING OF WILLIAM H. LELAND, ALBERT J. GIFFORD, AND SUBBO NIKOLOFF.

POWER-TRANSMISSION BELT.

1,223,513.

Specification of Letters Patent. Patented Apr. 24, 1917.

Application filed November 30, 1914. Serial No. 874,673.

To all whom it may concern:

Be it known that I, SUBBO NIKOLOFF, a citizen of the United States, residing at Putnam, in the county of Windham and State of Connecticut, have invented a new and useful Power-Transmission Belt, of which the following is a specification.

This invention relates to a belt for transmitting power at high speeds. In running certain classes of light tools at a speed of approximately 10,000 revolutions per minute I have found that the ordinary belts, both of leather and textile material, are entirely inadequate for the purpose. Many of the ordinary belts will not last even a single day on these high speed machines. I find that the leather belts usually break while the belts made of textile material or of cord stretch out so as to be useless after very little use, or break.

The principal object of this invention is to provide a light belt of such construction that the extremely rapid alternate flexing and straightening thereof will not cause it to give way readily so that it will stand this high service and will also be comparatively inexpensive and easily manufactured and applied.

Reference is to be had to the accompanying drawings in which—

Figure 1 is a side elevation of a portion of a machine showing a preferred embodiment of this invention applied thereto;

Fig. 2 is an elevation of a portion of the belt on an enlarged scale;

Fig. 3 is a longitudinal sectional view of the same through the center thereof;

Fig. 4 is a transverse sectional view of the stock for the belt before it is twisted, showing it in perspective, and

Fig. 5 is a transverse sectional view of the belt on the line 5—5 of Fig. 2.

For the purpose of providing a belt that will stand the service referred to, I manufacture it by securing together a plurality of pieces of narrow textile material, preferably in the form of tapes *a*. These pieces preferably are of different widths and arranged so that the narrower ones are on one side of the completed flat blank, and the wider ones on the other side, thus giving a beveled edge *b*.

Several tapes are secured together by sewing through them throughout their

lengths at *c*. Wherever the two ends of one of the tapes are connected by stitching *d*, all the other tapes are continuous. Thus they not only break joints, but these joints are arranged helically on the completed product and thus are not at right angles to the strain when in use. In securing them together they are given a sufficient amount of twist to give the belt a round form and bring the edges almost together but care is taken not to give them sufficient twist to cause their edges to press hard against each other or to overlap in any way. In twisting, the wide side of the blank is left on the exterior. In this way the contiguous external edges of the various convolutions of the belt come substantially into contact when the belt is stretched out straight so as to form a substantially continuous pulley contacting surface. But even when bent around a small pulley the edges of the inner plies do not press hard upon each other or cause any undue wear at these points. Furthermore as the belt passes over the pulley the edges on the convex side will separate readily and naturally without producing any undue strain on any part of the belt or any wear on each other.

I find in practice that a belt so made is capable of being used at the highest speeds known to present shop practice and on pulleys of a minimum diameter and that the life of the belt is increased by many hundred per cent. over any known in any ordinary shop practice. The ready flexibility of the belt at the points at which the edges of the tape come together is partly responsible for this and the manner in which the edges of the convolutions come together is also an important feature.

It will be understood that the fabric preferably is not treated in any way in order to give the belt its shape or hold it in position but when the belt is ready to be put on the pulleys its outside surface which comes into contact with the pulley surfaces is treated with ordinary shoemakers' wax or some equivalent thereof.

In use I find that the belt has great powers of transmission but its principal value is the fact that it can be used for this high service on pulleys of very small diameters and that its life is exceedingly great.

Although I have illustrated and described

only a single embodiment of the invention, I am aware of the fact that many modifications can be made therein by any person skilled in the art without departing from the scope of the invention as expressed in the claims.

Therefore I do not wish to be limited to all the details or features of construction herein shown and described, but

10 What I do claim is:—

1. As an article of manufacture, a belt for transmission at high speeds, comprising a plurality of plies of narrow woven fabric of different widths, said belt being given a sufficient amount of twist to give the belt a round form and bring the edges at the surface substantially together so as to form a smooth outer surface but not sufficient to cause the edges in the interior to press hard
- 15

against each other or overlap, whereby the edges of the inner plies do not wear on each other in use.

2. As an article of manufacture, a round belt consisting of a plurality of plies of narrow woven fabric twisted together, the two ends of each ply being secured together end to end at different places along the length of the belt so as to form seams, breaking joints, and the different plies being secured to each other by sewing through them.

In testimony whereof I have hereunto set my hand, in the presence of two subscribing witnesses.

SUBBO NIKOLOFF.
